GARMENT HANGER

John H. Batts, Grand Rapids, Mich., assignor to John Thomas Batts, Inc., Zeeland, Mich., a corporation of Michigan

Filed Feb. 13, 1967, Ser. No. 5,815

Term of patent 14 years

(Cl. D80—8)

FIG. 1 is a perspective view of a garment hanger showing my new design;

FIG. 2 is a rear elevational view thereof;

FIG. 3 is an elevational view taken from one side thereof;

FIG. 4 is a top plan view thereof; and

FIG. 5 is a cross sectional view taken on line V—V of FIG. 2.

The characteristic features of this design reside in the lower end portions of the hanger arms, and the junction of these ends to the cross bar.

I claim:

The ornamental design for a garment hanger, substantially as shown and described.
